UNITED STATES PATENT OFFICE.

KARL MARTIN JOHANSSON, OF STOCKHOLM, SWEDEN.

METHOD OF AND MEANS FOR MANUFACTURING LATHING FOR WALLS AND CEILINGS.

Application filed September 16, 1926, Serial No. 135,884, and in Sweden May 20, 1926.

It is known to manufacture reinforced lathing comprising a wire-netting the wires of which are rigidly connected together at the crossing points, and reed pipes or the like secured to said wire-netting. In order to fasten said reed pipes or the like to the wire-netting there has been already proposed a sewing operation in which the reed pipes are fastened to the wire-netting by means of under and upper threads, preferably metal threads or wires.

Such a sewing operation, however, cannot be suitably carried out by means of a machine and, in fact, no machines to effect such sewing operation have hitherto been designed.

This invention has for its object to provide a simple and reliable method of manufacturing reinforced lathings and a machine for carrying said method into effect on a commercial and economical basis.

The invention is characterized chiefly by the fact that the reed pipes or the like are fastened to the wire-netting by means of a number of single threads or wires which are bent through meshes of the wire-netting from one side thereof to form loops on the opposite side of the netting to receive a reed pipe or the like, said loops after the introduction of the reed pipe being contracted so as to hold the reed pipe firmly to the wire-netting.

The method will be best understood from a description, taking into consideration the annexed drawing which shows one embodiment of a machine whereby the method may be carried out.

In the drawing, Figure 1 is a side elevation of said machine with certain parts removed.

Figure 1^a is a side elevation of the operating parts of said machine showing another position thereof.

Figure 2 is a front elevation of the machine with parts removed.

Figure 3 is a side elevation and

Figure 4 is an edge view on a larger scale of the means for displacing the looper shaft.

Figure 5 is a side elevation on the same scale of means to impart an oscillating motion to said looper shaft.

Figure 6 is a side elevation of the wire-netting feeding mechanism.

Figure 7 is a side elevation with part in section of a needle.

Figure 8 is a perspective view of part of a lathing according to this invention.

With reference to the drawing, a frame 1 supports a wire-netting supply drum (not shown), upon which the wire-netting is wound. From said supply drum the wire-netting 2, Figure 1, is passed over guiding rollers 3 carried by arms 4 and adapted to keep the wire-netting in engagement with a transversely extending feeding roller 5 mounted on the top of the frame 1 at one end thereof, the wire-netting passing below said feeding roller from said guiding roller. From the feeding roller 5 the wire-netting is passed to a drum 6 adapted to receive the finished lathing, said drum being situated at the opposite end of the frame to that at which the roller 5 is situated. On the way between the feeding roller 5 and the receiving drum 6, reed pipes or the like are attached to the wire-netting in the manner hereinafter described.

The feeding roller 5 is controlled from the main shaft 7 of the machine which extends over the entire width of the frame 1 and is carried by bearings 8 attached to a framework 9 resting on the top of the frame 1. Said main shaft 7 may receive its power from any desired source, not shown. Keyed to the shaft 7 is a cam disc 10, Figure 7. Engaging said cam disc from opposite sides thereof are two levers 11, 12 carrying anti-friction rollers 13, 14. The lever 11 is mounted at its one end on a stationary shaft, as shown at 15, and is connected at an intermediate point by a link 16 to a lever 17 rotatably mounted on the shaft 18 of the feeding roller 5. Said lever 17 carries a pawl 19 meshing in a ratchet wheel 20 rigidly secured to the shaft 18 or to the roller 5. The lever 12 is, likewise, mounted on a stationary shaft, as shown at 21, and is connected by a link 22 to a bell crank lever 23, rotatably mounted on the shaft 24 of the receiving drum 6 and carrying a pawl 25 meshing in a ratchet wheel 26 rigidly secured to said shaft 24 or to the drum 6. Associated with the feeding roller 5 and the receiving drum 6 are also suitable means to prevent unintended or too rapid movements thereof. Said means are not illustrated in the drawing, as they may be of any well-known type desired.

Cooperating with the wire-netting or the lathing is also a guiding roller or drum 27,

Figure 1, to maintain the wire-netting in a straight condition during the sewing operation.

Attached to a transverse shaft 28 mounted on the top of the frame 1 is a number of arms 29. Each of said arms carries near its free end an arc-shaped needle 30. Each arm 29 also carries at its free end a rotatable roller 31 to guide the needle thread which may comprise a small gauged iron wire or the like. At a point between the needle 30 and the shaft 28 each arm 29 carries a similar roller 32. The free end of the needle 30 is pointed, and near said pointed end the needle is formed with an eye of sufficient size to permit the mounting therein of two rollers 34, 35 of small dimensions to guide the fastening or needle thread or wire 36. Leading to said eye is a groove 33, Figure 7, formed in the convex side of the needle to guide said thread or wire.

The wire used as fastening thread is supplied for each needle arm 29 from a supply reel 37 mounted upon the top of the frame-work 9. From its respective reel each wire passes under a roller 38 on the front of the framework 9 and from thence upwardly through a take-up 40 carried by a spring 39. From said take-up the thread passes under a stationary roller 41 mounted on the top of the frame 1 and is then passed upwardly over the roller 32 and downwardly under a second stationary roller 42 on the top of the frame 1, and from thence round the roller 31, down through the groove 33, between the rollers 34, 35, and is then fastened with its free end to the wire-netting 2 in any suitable way.

Immediately in front of the path of the needles 30 the wire-netting passes through a stationary guide-way comprising, for instance, angle-bars 43, 44, to prevent the wire-netting from vertical movements.

The needle arms 29 are adapted to oscillate up and down between the upper extreme position, shown in Figure 1, and the lower extreme position, shown in Figure 1^a. Formed in the top of the frame 1 is a depression, as shown at 100, corresponding to the path of the needles, the purpose of which will be obvious as the description proceeds. The movement of the needle arms 29 is derived from the main shaft 7 by means of a cam slot disc 45 keyed thereto and a cam follower 47 engaging the slot 46 of said disc 45, said cam follower being keyed to the common shaft 28 of the needle arms 29.

Provided in register with said depression in the top of the frame 1 are a number of funnel-shaped sheet-metal members 48 serving to receive the reed pipes or the like to be fastened to the wire-netting 2. In Figure 1^a such a reed pipe is indicated at 49.

Slidably and rotatably mounted in bearings 52, 53 supported by a cross bar 50 of

the frame 1 is a transversely extending shaft 51. Said shaft 51 carries a number of upwardly projecting arms 53, one for each needle arm 29, said arms 53 having at their upper ends a laterally extending projection 54. Acting on one of the arms 53 (as seen to the right in Figure 2) is a coiled spring 55, tending both to maintain the arms 53 in the angular position shown in Figures 1 and 1^a and to keep the shaft 51 displaced to the left, Figure 2, so as to maintain the projections 54 out of the paths of the respective needles 30. The shaft 50 may be displaced against the action of said spring 55 by power derived from the main shaft 7 by means shown in Figures 3 and 4. Such means comprise a cam 56 on the cam disc 45, an arm 58 pivoted at 57 which is controlled by said cam; a link 59 connecting a second arm 58^a on the shaft 57 to an arm 61 attached to the longitudinally-extending journal 60 and a further arm 62 secured to said journal 60 which engages one end of the shaft 51.

To rotate the shaft 51 against the action of spring 55 the following means are provided. Keyed to shaft 7 is a cam 63, Figure 6. Said cam is engaged by an antifriction roller 64 mounted at one end of a bell crank lever 66 pivoted at 65, the other end of which is connected by a link 67 to an arm 68 on the shaft 51. This arrangement is designed to operate in conjunction with the spring 55 to impart an oscillating movement to the shaft 51 so as to cause the arms 53 to oscillate between the two extreme positions indicated in Figure 1^a.

The bell crank lever 66 is also used to impart an oscillating motion to a transverse shaft 69 by means of a link 70 and an arm 71 on said shaft. The shaft 69 carries a number of arms 72, Figures 1 and 1^a, extending to the paths of the needles 30, said arms being adapted upon the movement of the shaft to oscillate between the two extreme positions shown in Figure 1^a.

The operation of the machine is as follows:

The wire-netting is moved step-wise along the top surface of the frame 1 from the feeding roller 5 to the receiving drum 6, the wire-netting in said movement passing through the stationary guide-way 43, 44 and under the drum 27 so as to be kept in a straight horizontal state when passing the depression in the top surface of the frame 1.

The shaft 7 is assumed to rotate in the direction indicated by the arrow in Figure 3. The position shown in Figure 3 corresponds to the position shown in Figure 1. The needle arms 29 are at this moment in their uppermost position, the shaft 51 is pushed to the left and turned back by the spring 55, and the arms 72 are in their uppermost position. In the continued rotation of shaft 1^a

7 the arm 47 is turned down by the cam 46 causing the needle arms 29 with the needles 30 to simultaneously descend. The needles will each pass down through a mesh of the 10 wire-netting which is now in rest, because of the fact that, as is obvious from Figure 6, the pawls 19 and 25 will by this time slide back on their respective ratchet wheels without operating same. As the needle arms 15 descend the threads 36 previously lying in zig-zag in the raised position of said arms will slacken according as the arms descend, the zig-zag shape of the threads being thereby substantially removed. When the needle 20 arms 29 reach their lowermost position the cam 56 will engage the arm 58 to swing it to such an extent as to push the shaft 51 to the right, Figure 2, thereby causing the projections 54 to engage the respective loops of 25 the fastening threads formed on the under side of the wire-netting as a result of the above-described downstroke of the needles 30. This being ended, the cam 63 commences to operate the bell crank lever 66 to rotate 30 the shaft 51 against the action of the spring 55 thereby moving the arms 53 to the position shown by dotted lines in Figure 1^a.

As a result, the projections 54 engaging 35 in their respective loops of the fastening threads 36 will widen same to an extent substantially corresponding to the openings of the funnels 48. At the same time that the shaft 51 is rotated in this way the shaft 69 is also rotated, causing the arms 72 to swing 40 downwardly, so that the arms 72 will reach the position shown by dotted lines in Figure 1^a by the time that the arms 53 reach their position, shown by dotted lines in the same drawing. At this moment a reed pipe or the 45 like is introduced, as by hand, into the funnels 48, said reed pipe being thereby also introduced into all of the loops of the threads 36. As shown in Figure 1^a the arms 72 in this position extend with their free end beyond said 50 reed pipe. The various cams on the shaft 7 are designed so that this position will be maintained for a sufficient period of time, that is, for about $\frac{2}{3}$ of a revolution of the shaft 7, to give ample time to the operator to introduce the reed pipe. When the circular portion of cam 63 leaves the lever 66 the latter is allowed to swing back again under the action of the spring 55 which at the same 55 time pushes back the shaft 51 to the left so as to release the projections 54 from their engagement in the loops, as soon as the cam 56 releases the lever 58. At the same time the shaft 69 is also turned back to cause the arms 72 to swing upwardly. The arms 72 60 in this movement will lift the reed pipe or the like causing it to slide along the arms 53 till it comes into contact with the under-side of the wire-netting. The cam slot disc 45 will then again turn the arm 47 and with 65 it the needle arms 29 upwardly to cause the threads 36 to be again lifted, thereby contracting the loops till the threads 36 will hold the reed pipe firmly against the under side of the wire-netting. The loops are taken up by the threads 36 being again given their 70 zig-zag shape, and any remaining slack of the threads will be removed by the spring-controlled take-up rings 40. The feed motion device is now set into motion and moves the wire-netting or lathing to the position 75 for receiving the next reed pipe or the like whereupon the cycle of operation again takes place.

In finished state the lathing is of the appearance shown in Figure 8. The reed pipes 80 49 attached to the wire-netting 2 at one side thereof by means of the threads 36, will, when the lathing is placed on a wall or ceiling to be riveted, maintain the wire-netting at a suitable distance from said wall 85 or ceiling so that the wire-netting after the application of the plaster will form a reinforcement situated substantially in the middle of the plaster.

It is to be noted that the details of the 90 machine may be varied without departing from the principle of the invention.

What I claim is:

1. A method of manufacturing lathing which comprises taking a wire-netting, 95 stretching a number of substantially parallel single wires over one side of said netting, bending said wires through meshes of the netting so as to form loops on the opposite side of the netting, introducing reinforcing 100 bars through said loops, and contracting the loops so as to cause the wires to hold the bars firmly to the wire-netting.
2. A method of manufacturing lathing which comprises taking a wire-netting, attaching a number of continuous single wires with their one end to said wire netting, stretching the wires in substantially parallel directions over one side of said wire-netting, bending the wires through a transversely extending row of meshes of the netting so as to 105 form loops on the opposite side of the wire-netting, introducing a reinforcing bar in said loops, contracting the loops so as to cause the wires to hold the bar firmly to the 110 wire-netting, again bending the wires through another transversely extending row of meshes and so on.
3. A machine for manufacturing lathing comprising means for carrying a wire-netting, means for individually supporting wires adapted to be fastened with one end to the wire-netting in substantially parallel directions over one side of said wire-netting, and means for bending said wires through 120 meshes of said netting so as to form loops on the opposite side of said netting, lying in register with each other as seen in the transverse direction of the netting.
4. A machine for manufacturing lathing 125

comprising means for carrying a wire-netting, means for individually supporting wires adapted to be fastened with one end to the wire-netting in substantially parallel directions over one side of said wire-netting, means for bending said wires through meshes of said netting so as to form loops on the opposite side of said netting lying in register with each other as seen in the transverse direction of the netting, and means to facilitate the introduction of reinforcing bars through said loops.

5. A machine for manufacturing lathing comprising means for carrying a wire-netting in a substantially horizontal plane, individual reels to support wires adapted to extend in substantially parallel directions from said reels over one side of said netting to be fastened thereto with one end, individual means cooperating with such wires to take up a sufficient amount of wire from the respective reels and bend it through transversely extending rows of meshes of the netting, means to widen each of the loops thus formed on the opposite side of the netting, and means to facilitate the introduction of a reinforcing bar through a row of loops thus formed and widened.

6. A machine for manufacturing lathing comprising means for carrying a wire-netting in a substantially horizontal plane, individual reels to support wires adapted to extend in substantially parallel directions from said reels over one side of said netting to be fastened thereto with one end, individual means cooperating with such wires to

take up a sufficient amount of wire from the respective reels and bend it through transversely extending rows of meshes of the netting, means to widen each of the loops thus formed on the opposite side of the netting, means to facilitate the introduction of a reinforcing bar through a row of loops thus formed and widened, and means to move said bar towards the netting to facilitate contraction of the wire loops.

7. A machine for manufacturing lathing which comprises means to support a wire netting in a substantially horizontal plane, means to move said netting in a step-by-step motion over said supporting means, individual reels to carry wires adapted to extend over one side of said wire-netting in substantially parallel directions to be fastened thereto with one end, curved needles engaging the individual wires to take up sufficient amounts thereof on their way from said reels to the wire netting, means to cause said needles with the wires to move to and fro through meshes of the netting, means to engage and widen the loops of wires thus formed on the opposite side of the netting, means to facilitate the introduction of reinforcing bars in said loops, and means to move said bars towards the netting so as to facilitate the retraction of the needles with the wires through said meshes in order to cause the wires to hold the bars firmly to the netting.

In testimony whereof I have signed my name.

KARL MARTIN JOHANSSON.
